UNITED STATES PATENT OFFICE.

CHARLES ELMER COX, OF EATON, OHIO.

MULTIPLE LIGHTNING-ARRESTER.

1,124,865.

Specification of Letters Patent.

Patented Jan. 12, 1915.

Application filed October 25, 1912. Serial No. 727,670.

To all whom it may concern:

Be it known that I, CHARLES ELMER COX, a citizen of the United States, residing at Eaton, in the county of Preble and State of Ohio, have invented certain new and useful Improvements in Multiple Lightning-Arresters, of which the following is a specification, reference being had therein to the accompanying drawing.

10 My invention relates to multiple lightning arresters and more particularly to multiple line protective devices for telephonic or telegraphic lines.

15 The object of the invention is to provide a cheap, compact and efficient protective device for the protection of telephone and telegraph equipment against lightning and other electric disturbances, adapted to be mounted upon the line supporting means such as the yard or cross-arm of a line-pole and to take care of a plurality of lines such as all the lines carried by a single cross-arm or all the lines carried by a single pole.

20 A further object is to provide such a device of maximum durability by embodying the same in a structure of a maximum number of relatively massive parts.

25 The invention, however, is not limited merely for use on a line-pole but is also adapted for use in a junction box or in any other situation where a plurality of lines to be protected run along the same path or converge upon a common point.

30 My invention is illustrated in the accompanying drawings in which:

35 Figure 1 is an axial cross-section of the device assembled. Fig. 2 is a top plan view with the outer parts removed. Fig. 3 is a general view showing the device mounted on the cross-arm of a line-pole and the manner of connection.

40 Referring to Figs. 1 and 2, the main body of the device consists of a block of insulating material 1 in the form of a truncated cone having a recess extending upwardly from the base so as to form a chamber 2 with an annular side wall 3 and a relatively massive upper wall or top 4. The top is perforated near the circumference to form a circular series of ducts 5 extending between the chamber 2 and the top surface 8. Fitted into each of these ducts is a conductor 6 having its upper end 7 enlarged and dressed down flush with the top surface 8. The

lower end of each conductor 6 extends downward into the chamber 2 and is threaded to receive a pair of lock nuts 9. The top 4 is also centrally perforated to form a duct 10 in which is fitted a ground bolt or conductor 11. The ground conductor 11 is threaded at its upper end to receive the clamping means or lock nuts 15, and is also threaded at its lower end to receive the lock nuts 16.

Upon the surface 8 of the top 4 is placed a thin perforated spacing disk 12 of mica, or other insulating material. Upon this spacing disk 12 is placed a circular ground plate 14. The spacing disk 12 and ground plate 14 have substantially the same diameter as the upper surface of the top 4 and are centrally perforated to pass over the upper end of the ground conductor 11 through means of which and the lock nuts 15 they are clamped into place. Other forms of spark gaps may be used in place of the disk 12, the essential feature of my invention being the grouping of the spark gaps.

50 Outlet holes 17 corresponding in number to the number of conductors 6 are provided in the wall 3 for the passage of the spider wires 18 which wires are connected to the conductors 6 by means of the lock nuts 9 and lead out to the different lines to be protected. The ground wire 19 enters through a hole 20 near the base and is connected to the ground conductor 11 by means of the lock nuts 16.

55 The upper portion of the device is provided with a protective can or cover 21, adapted to wedge down over the outside of the tapering wall 3, and form a watertight closure for the spark gaps.

60 The whole device is adapted to be mounted upon the cross arm of a line pole by means of the brackets 22 bolted to the circular wall 3 at its base.

65 The duct 10 is shown recessed at its upper end to receive a collar 23 formed integrally with the ground conductor and below the surface 8, so that the ground conductor can be held rigidly in position independently of the nuts 15, thus facilitating the initial assembling and subsequent inspection of the spark gaps, or the adjustment of the spacing disk and ground plate. Other means for binding the ground conductor may be substituted for the shoulder, such as a nut threaded to the upper end of the ground conductor. The conductor 11 forms a guide

rod for keeping the peripheries of the members 10 and 12 in register with the upper edge of the body portion 1.

Fig. 3 illustrates the manner in which the device is installed on a line-pole. The body portion (1) of the device is secured to the upper surface and at the center of a cross arm 24 by means of the brackets 22, the different spider wires 18 are connected to the different line wires 25, respectively, and preferably insulated from each other by insulation of a thickness greater than the width of the spark gap, and the ground wire 19 is connected to ground in a well known manner.

Although I have shown the device mounted upon the top of a cross arm, it is not limited to this particular method of installation but may be mounted in various positions as called for by different conditions.

It is to be understood that I do not limit myself to the specific embodiment of the invention as herein illustrated and described, but contemplate all such variants thereof as will fall within the scope of the appended claims. For example; the holes 17 and 20 may be provided with suitable means to prevent the entrance of moisture; any well known means of connection may be substituted for the lock nuts 9 and 16; the lugs or brackets 22 may be integral with the body portion 1, and further, the body portion may be rectangular instead of circular in form.

Having thus described my invention what I claim and desire to secure by Letters Patent is:

1. In a lightning arrester, the combination of an insulating body in the form of an inverted cup having a recess extending upwardly from the base so as to form a skirted chamber with a transverse upper wall, conducting members extending from within the chamber through the upper wall to the upper surface thereof, a ground plate extending over the upper surface and the ends of the conducting members, a spacing member interposed between the ground plate and the upper surface having perforations in register with the ends of the conducting members, an additional conducting member extending from within the chamber through the upper wall and said spacing means and terminating in electrical contact with the ground plate, inlet holes in the skirt of the chamber for the admission of wires to the conducting members within

the chamber and a protective cover adapted to inclose the upper portion of the insulating body and the ground plate.

60

2. A lightning arrester comprising the following instrumentalities: an insulating body in the form of an inverted cup with a flat horizontal head, line terminals and a ground terminal spaced apart and extending through said head, with their upper ends exposed on the outside thereof and the lower ends lying within the chamber of the cup so as to be entirely surrounded by the side walls thereof, a ground plate overlying the exposed ends of the terminals on the upper side of the head and in metallic connection with said ground terminal, insulating and spacing means interposed below the ground plate to maintain the same above the exposed ends of the terminals, leaving clear discharge gaps over said terminals and a clear opening for the passage of the ground terminal, and means for connecting line wires to the lower ends of all the terminals within the cup of the insulating body.

3. A lightning arrester comprising the following instrumentalities: an insulating body in the form of an inverted cup with a flat horizontal head, and a surrounding skirt, line terminals and a ground terminal spaced apart and extending through said head, with their upper ends exposed on the outside thereof and the lower ends lying within the chamber of the cup so as to be entirely surrounded by the skirting side walls thereof, a ground plate overlying the exposed ends of the terminals on the upper side of the head and in metallic connection with said ground terminal, an insulating spacing plate interposed between the ground plate and said exposed ends of the terminals with openings registering with said terminals and a separate opening for the passage of the ground terminal, and means for connecting line wires to the lower ends of the terminals within the cup of the insulating body, and a top or cover extending over and completely inclosing the ground plate and terminals, with its side walls embracing and touching the sides of the insulating body.
